UNITED STATES PATENT OFFICE

**ABRAHAM T. GOLDFIELD, OF SPRING VALLEY, NEW YORK, ASSIGNOR TO NEW YORK
CLOCK CORPORATION, A CORPORATION OF NEW YORK**

DESIGN FOR A CLOCK CASE

Application filed June 2, 1927. Serial No. 22,287. Term of patent 7 years.

To all whom it may concern:

Be it known that I, ABRAHAM T. GOLDFIELD, a citizen of the United States of America, residing in Spring Valley, Rockland County, State of New York, have invented a new, original, and ornamental Design for a Clock Case, of which the following is a specification, reference being had to the accompanying drawing, forming a part thereof.

In the drawing I have illustrated only a portion of the surface ornamentation of my new design, but it is to be understood that

such ornamentation is continued around the clock.

In the drawing, Fig. 1 is a front view of a clock case illustrating my new design, and Fig. 2 is a side view thereof on a reduced scale.

I claim:

The ornamental design for a clock case, substantially as shown and described.

This specification signed this 1st day of June, 1927.

ABRAHAM T. GOLDFIELD.
